[57] CLAIM

The ornamental design for a front surface of a retaining wall module, as shown and described.

DESCRIPTION

FIG. 1 is a perspective view of a first embodiment of the front face of a retaining wall module shown in condition of use with other retaining wall blocks;

FIG. 2 is a greatly enlarged view of the front face of a retaining wall module shown in FIG. 1 shown separately for clarity of illustration;

FIG. 3 is a perspective view of a second embodiment of the front face of a retaining wall module shown in condition of use with other retaining wall blocks;

FIG. 4 is a greatly enlarged view of the front face of a retaining wall module shown in FIG. 3 shown separately for clarity of illustration;

FIG. 5 is a perspective view of a third embodiment of the front face of a retaining wall module shown in condition of use with other retaining wall blocks;

FIG. 6 is a greatly enlarged view of the front face of a retaining wall module shown in FIG. 5 shown separately for clarity of illustration;

FIG. 7 is a perspective view of a forth embodiment of the front face of a retaining wall module shown in condition of use with other retaining wall blocks; and,

FIG. 8 is a greatly enlarged view of the front face of a retaining wall module shown in FIG. 7 shown separately for clarity of illustration.

The broken line showing of a sectional retaining wall is for illustrative purposes only and forms no part of the claimed design.
